ALABAMA

SANITARY COMMODE

Application filed November 22, 1928, Serial No. 321,143. Renewed November 11, 1929.

The invention aims primarily to provide a new and improved commode construction which is absolutely tight and fly-proof when not in use and is provided with unique spring-operated means insuring lowering of both a pivoted seat and its cover after using the commode as a urinal, and insuring closing of said cover after use with only the cover raised, novel provision being made whereby weight upon the seat holds the seat cover out of operative relation with said spring-operated means, so that the cover will not bear with force upon the user's back.

A further aim is to provide a seat and cover and closing means therefor which may be used with various kinds of closets.

Yet another aim is to provide a new and improved hopper construction, that shown being intended primarily for a cement-topped pit toilet.

With the foregoing in view, the invention resides in the novel subject matter hereinafter described and claimed, description being accomplished by reference to the accompanying drawings.

Fig. 1 is a side elevation of a commode constructed in accordance with our invention.

Fig. 2 is a rear elevation partly in section.

Fig. 3 is a vertical sectional view on the plane of line 3—3 of Fig. 2.

Fig. 4 is a longitudinal sectional view showing the relation of parts which exists when the cover is raised and the seat occupied.

Fig. 5 is a top plan view partly broken away and in horizontal section.

Fig. 6 is a detail vertical sectional view showing the relation of parts existing when the seat and cover are both raised for use of the commode as a urinal.

Fig. 7 is a fragmentary vertical section showing a modified form of construction.

The structure herein disclosed may be considered as preferred, and while such structure will be specifically described, it is to be understood that within the scope of the in-

vention as claimed, variations may be made.

We employ a continuous base ring 8 which is vertically widened and is adapted in most instances to be inset around an opening in the cement top of a pit, said base ring being provided with a laterally off-set portion 9 having an upstanding collar 10 to which a vent pipe 11 is connected. The upper edge portion 12 of the ring 8 is preferably offset inwardly to some extent from the body portion of said ring and is received in the lower end of a hopper wall 13, said wall end being provided with an outstanding flange 14 through which bolts 15 pass to secure the wall 13 to outstanding lugs 16 upon the ring 8. If the device is to be used in some relation other than with a pit, for instance, if it is to enclose a container, either the ring 8 may be secured directly upon a floor or the entire base ring 8 may be dispensed with and the flange 14 secured upon the floor.

Movably received within the upper portion of the wall 13, is a seat-carrying ring 17, said ring being provided with a rearwardly projecting flange 18 which rests normally upon the upper edge of the wall 13, said flange having portions which extend forwardly at the sides of the ring 17 and terminate in transverse shoulders 19 forming pivots upon which the ring 17 may tilt, the rear portion of the ring moving upwardly when the front portion thereof is depressed. Normally, the rear portion of the ring 17 is lowered and the front portion raised as seen for instance in Figs. 1 and 3, being held in this position by spring means hereinafter described, and to limit the movement of the ring under this spring means, we prefer to provide said ring with a flange 20 normally underlying a flange 21 which extends inwardly from the upper end of the wall 13.

Hinge posts 22 are secured to and rise from the flange 18, said posts carrying a transverse hinge rod 23 upon which a seat 24 and cover 25 are pivotally supported, said cover 25 hav-

ing a portion 26 which moves downwardly toward the flange 18 when said cover is swung rearwardly past a vertical position. Under this cover portion 26, is a vertical rod 27 whose upper portion passes slidably through a guide on the rear portion of the ring 17, said guide being in the present instance formed by a portion of the flange 18, which portion is provided with an opening 28 through which the 10 rod 27 passes. The lower portion of the rod 27 passes through a lower guide fixedly carried by the rear of the wall 13. In the present showing, this guide is formed by the apertured bottom 29 of a small casing 30 which 15 is secured to said rear portion of the wall 13, the rod 27 being slidably received in the aperture 31 of said casing bottom. A coiled compression spring 32 surrounds the rod 27 within the casing 30 and bears at its upper end 20 against a collar or the like 33 secured to said rod. The lower end of this spring contacts with an eye 34 on the lower end of a hanger bolt 35 whose upper end is adjustably connected with the flange 18. The lower end of rod 25 35 40 45 50 55 60 65 70 75 80 85 90 95 100 105 110 115 120 125 130 27 is provided with a nut or other stop 36 which may be adjusted to limit the ascent of said rod under the action of the spring 32 and to dispose the upper extremity 37 of said rod in proper relation with the portion 26 of the seat cover 25. When the parts stand in normal position as seen for instance in Figs. 1, 2 and 3, spring 32 exerts downward force upon the hanger bolt 35, thus pulling downwardly upon the flange 18 and holding the entire ring 17 with its front portion raised to the limit dictated by the flanges 20—21. The upper extremity 37 of the rod 27 is now in the path of the seat cover portion 26, if the latter be raised for any cause and forced rearwardly 40 beyond a position at which it would close by gravity. Hence, upon such movement of the cover 25, for instance when raising both this cover and the seat 24 as seen in Fig. 6 for use of the device as a urinal, the cover portion 26 will strike the upper end 37 of rod 27, thereby depressing the latter against the action of the spring 32 as shown in said figure. Both the seat and the cover must be held in this position as long as required, for as soon as 50 they are released, the spring 32 forces the rod 27 upwardly, thus thrusting against the cover portion 37 and effecting forward and downward swinging of both seat and cover.

When the seat 24 is to be occupied, the cover 55 60 65 70 75 80 85 90 95 100 105 110 115 120 125 130 25 is raised and temporarily held against the action of the rod 27 and the spring 32, but as soon as weight is placed upon the seat 24, the front portion of the ring 17 is depressed as shown in Fig. 4, thereby raising the rear portion of said ring and causing the flange 18 and the mounting means for the seat and cover to rise. In so rising, the cover portion 26 is moved to or slightly beyond the uppermost position of the head 37 of the rod 27, so that the cover will then have no tendency

to close. Just as soon however as weight is relieved from the seat 24, the spring 32 which has been compressed by movement of the ring to the position of Fig. 4, restores this ring to the normal position of Fig. 3. In moving in this manner, the rear portion of the ring necessarily descends, causing the cover portion 26 to strike the upper extremity 37 of the rod 27, so that a forward and downward movement is imparted to said cover, insuring that it shall close as soon as the seat is vacated.

In Fig. 7 a modified form of construction is shown which may be used in some instances if desired. In this view, 27^a denotes a rod similar to rod 27 passing through the opening 28 of the flange 18 and provided with a head 37^a above said flange. The lower end of this rod passes through a lower guide 29^a secured to the hopper wall 13, and said lower end of the rod is provided with a nut or the like 36^a normally abutting the lower side of said guide 29^a. This guide 29^a may if desired be the bottom of a casing such as 30, but may merely be a lug or bracket as shown. A coiled compression spring 32^a surrounds the rod 27^a between its head 37^a and the flange 18. This relation of parts performs exactly the same work as the construction above described but is not so desirable in view of the facts that the spring 32^a is exposed and the parts cannot be so readily lubricated. When the casing 30 is employed, not only is the spring 32 encased, but said casing may be used to contain a lubricant.

It will be seen from the foregoing that although our invention is rather simple and inexpensive, it will be efficient and in every way desirable, always producing a tight fly-proof structure having an unusual element of sanitation.

We claim:

1. In a sanitary commode, a seat cover, a seat carrier on which said seat cover is pivoted, a closing device for said cover positioned to engage and act upon said cover when the latter is raised to use the commode only as a urinal, means mounting said carrier for depression under weight, depression of said carrier serving to move said cover and said closing device out of co-operative relation, and means for raising said carrier and placing said cover and said closing device again in co-operative relation when the carrier is freed of weight.

2. In a sanitary commode, a depressible seat carrier, a hinged seat cover mounted on said carrier, and yieldable means for normally holding said carrier in raised position; said yieldable means embodying a yieldable portion against which the cover must be forced in order to raise said cover to a vertical position, whereby said yieldable portion acts to close the cover if raised to an extent at which gravity cannot close it; said seat carrier when depressed serving to move said

cover and said yieldable portion out of co-operative relation and when again raised serving to restore them to co-operative relation to effect cover-closing.

5 3. A sanitary commode comprising a stationary wall, a seat carrier pivotally mounted near its rear portion on said wall to permit depression of the main portion of said carrier under weight and to effect raising of said rear portion thereof concurrently with said depression, a seat cover pivoted on said rear portion of the carrier and having a portion which moves downwardly toward said rear portion when the cover is used, a depressible spring-raised cover-closing member mounted at the rear of said wall in the downward path of said downwardly movable cover portion, and a stop for limiting the upward movement of said member, whereby this member will be depressed by raising of the seat cover to a vertical position to later act for the purpose of closing said cover, the aforesaid raising of said rear portion of said carrier serving to raise said cover sufficiently 25 to prevent it from depressing said cover-closing member when the cover is raised.

4. A sanitary commode comprising a stationary wall, a seat carrier pivotally mounted near its rear portion on said wall to permit depression of the main portion of said carrier under weight and to effect raising of said rear portion thereof concurrently with said depression, a seat cover pivoted on said rear portion of the carrier and having a portion which moves downwardly toward said rear portion when the cover is raised, a substantially vertical rod behind said wall, upper and lower guides on the carrier and wall respectively, slidably receiving said rod, spring means forcing upwardly on said rod and downwardly on said upper guide, and a stop for limiting the upward movement of said rod to a position at which said downwardly movable portion of the cover will strike the rod and depress it against the action of said spring means upon forcing of the cover to a vertical position, the aforesaid raising of said rear portion of the carrier serving to permit full opening of said cover without depressing said rod but leaving the latter in readiness to effect cover closing upon removal of weight from the carrier.

5. A sanitary commode comprising a continuous wall, a seat-carrying ring pivotally mounted near its rear portion on the upper end of said wall to permit depression of the main portion of said ring under weight and to effect raising of said rear portion of the ring concurrently with said depression, a seat cover pivoted on said rear portion of said ring and having a portion which moves downwardly toward said rear portion when the cover is raised, a substantially vertical rod behind said walls, upper and lower guides 65 on the ring and wall respectively and slid-

ably receiving said rod, spring means forcing upwardly on said rod and downwardly on said upper guide, and a stop for limiting the upward movement of said rod to a position at which said downwardly movable portion of the cover will strike the rod and depress it against the action of said spring means upon forcing of the cover to a vertical position, the aforesaid raising of said rear portion of said ring serving to permit full opening of the cover without depressing said rod but leaving the latter in readiness to effect cover-closing upon removal of weight from the upper wall.

6. In a sanitary commode, an upstanding wall, a sheet-carrying ring movably received within the upper portion of said wall and provided with a rearwardly projecting flange having shoulders which rest upon the upper end of said wall and constitute pivots about which said ring may swing vertically, a seat and a cover therefor both hingedly supported by said flange, said cover having a portion which moves downwardly toward said flange when said cover is raised to vertical position, a spring-raised depressible cover-closing member having a portion spaced above said flange in position to be struck by said downwardly movable portion of the seat cover, and a stop for limiting the upward movement of said member with regard to said wall, depression of the front portion of said ring and consequent raising of said flange serving to sufficiently raise the cover to prevent depression of said member upon opening of said cover.

7. A structure as specified in claim 6; together with an outwardly projecting flange on the front portion of said ring and an inwardly projecting flange on the upper end of said wall, these flanges being co-operable with each other to limit the upward movement of said front portion of said ring.

8. In a sanitary commode, a vertical wall, a ring movably received within the upper portion of said wall and having a rearwardly projecting flange, said flange being provided with shoulders which rest upon the upper end of said wall and act as pivots about which the ring may vertically swing, said flange being provided with an opening, a vertical rod passing slidably through said opening, a fixed guide carried by the rear portion of said wall and slidably receiving the lower end of said rod, a stop on said rod normally abutting said fixed guide to limit ascent of said rod, spring means acting upwardly upon said rod and downwardly upon said flange, a seat and a cover therefor, and means pivotally mounting said seat and cover upon said flange, said cover having a portion to abut and depress said rod upon opening of said cover to a predetermined extent; depression of the front portion of said ring serving to elevate said flange sufficiently to prevent de-

pression of said rod by raising of said cover.

9. In a sanitary commode, a base ring having a lateral offset provided with a vent, lateral lugs disposed horizontally and projecting rigidly from the exterior of said ring, a hopper wall surrounding the upper portion of said ring and having an outstanding flange, bolts tying this flange to the aforesaid lugs, and closing means for the upper end of said wall embodying a seat and a seat cover.

10. In testimony whereof we have hereunto affixed our signatures.
